UNITED STATES PATENT OFFICE.

JOHN BARRON, OF ALBION, CALIFORNIA.

RAIL JOINT.

Application filed December 4, 1923. Serial No. 678,433.

To all whom it may concern:

Be it known that I, JOHN BARRON, citizen of the United States, residing at Albion, in the county of Mendocino and State of California, have invented certain new and useful Improvements in Rail Joints, of which the following is a specification.

This invention relates to rail joints, and it has for an object the provision of a novel type of rail joint which will serve to securely hold the rails together and will obviate danger of accidental loosening, while at the same time permitting ready disengagement of the rail ends from one another when desired.

For further comprehension of the invention and of the objects and advantages thereof, reference will be had to the following description and accompanying drawings, and to the appended claims in which the various novel features of the invention are more particularly set forth.

Fig. 1 of the drawings is a plan view showing my improved rail joint.

Fig. 2 is a side view thereof.

Fig. 3 is a transverse sectional view taken on the line 3—3 of Fig. 1.

Fig. 4 is a fragmentary perspective view, showing the chair element with one of the rails in place thereon.

Fig. 5 is a plan view showing the arrangement of parts at a cross-over or siding.

Fig. 6 is a transverse sectional view taken on the line 6—6 of Fig. 5.

Referring first to Figs. 1 to 4 of the drawings, my improved rail joint comprises a chair element in the form of a plate 10 upon which the rail ends rest, the adjacent rail ends being indented at 11 and 11', the plate being longitudinally recessed as at 12 to receive the feet of the rails. This plate presents a widened portion 14 midway between its ends forming integral projecting wings, while notches 15 are formed in the side edges of the plate at the ends of these wings, the feet of the rail ends being formed with notches 16 which register with the notches 15. Fitting over these projecting central parts 14 of the plate are the rectangular collars 17 which have apertures therein of a size to snugly receive the said parts, the inner edges of these collars bearing on the feet of the rails and holding the latter against tilting movement, the ends of these collars engaging in the registering notches 15, 16 in the plate and the feet of the rail,

and preventing longitudinal movement, sufficient play being left to allow of expansion and contraction of the rails under variations in temperature. To lock these collars in place each one is formed at its outer edge with a vertical web 17' which engages in a notch 18 in the plate element 14 midway between the ends of the latter, while a bolt 19 is slidably mounted in a suitable passageway 20 in the said element 14 and is adapted to be projected across the outer face of this web, this bolt having fixed thereto a handle 21 which passes through a transverse slot 22 communicating with the passageway 20 when the bolt is withdrawn to allow of removal of the collar. The rail ends are preferably slotted upwardly from the bottom thereof, while the plate has a central longitudinal fin 24 which engages in the slots in the rail ends. The plate 10 may have spike holes 27 formed therein to receive spikes whereby it may be secured to the ties.

In Figs. 5 and 6 I have shown the arrangement of the device where two rails are approaching one another. The chair plate 10^a is widened to extend under both rails, and at the outer sides of each rail the collars 17 are applied as above set forth. Extending along the plate 10^a midway between the rails is a grooved rib 30 upon which is slidably mounted a member 31 which engages at its sides over the feet of the rails, the parts being so proportioned that this member will be moved into and out of engagement with the feet of the rails by movement along the guide rib 30, the latter having parallel sides as will be understood, while the member is tapered at its sides in correspondence to the obliquity of the rails to be engaged. The member is provided at one end with a handle 33 and carries at its opposite end a bolt 34 adapted to removably engage behind a lug 35 on the plate to hold the said member in operative position.

While I have illustrated and described a preferred embodiment of my invention it is to be understood that I do not limit myself to the precise construction herein disclosed and that various changes and modifications might be made therein without departing from the spirit and scope of the invention as defined in the appended claims.

Having thus described my invention what I claim as new and desire to protect by Letters Patent of the United States is as follows:

1. A rail joint comprising a chair plate recessed along its top face to receive the feet of adjacent rail ends, said plate having integral lateral projections from opposite sides thereof, and a rectangular collar fitting over each of said projections and engaging the feet of the rail ends, said plate having notches in the sides thereof at the ends of said projections, and said feet having registering notches, the said collars engaging at their ends in the said notches.
2. A rail joint comprising a chair plate recessed along its top face to receive the feet of adjacent rail ends, said plate having integral lateral projections from opposite sides thereof, and a rectangular collar fitting over each of said projections and engaging the feet of the rail ends, said plate having notches in the sides thereof at the ends of said projections, and said feet having registering notches, the said collars engaging at their ends in the said notches, said projections having notches formed in the sides thereof between their ends, vertical webs in

the said collars engaging in the last named notches, and bolts carried by the said projections and adapted to engage behind the said webs. 25

3. A rail joint comprising a chair plate having lateral projections and collars engaged over these lateral projections and bearing on the rail ends, the rail ends being slotted upward from the bottom and the said plate having a fin engaging in the slots in the rail ends. 30

4. In combination, two pairs of rail ends inclined with respect to one another, a chair plate extending under said pairs of rail ends, projections on the sides of said chair plate, collars fitted on said projections and bearing on the feet of the rail ends, a guide rib on said plate midway between the rails, and a member slidable on the guide plate and adapted to engage over the feet of the rails. 35

In testimony whereof I have affixed my signature. 40

JOHN BARRON. 45
